US00D456561S

(12) **United States Design Patent** (10) Patent No.: **US D456,561 S**
 Freeman et al. (45) Date of Patent: ** Apr. 30, 2002

(54) **SOAP BAR**

(76) Inventors: **Scott H. Freeman; Faith Freeman**, both of 3632 Rebel Cir., Huntington Beach, CA (US) 92649

(**) Term: **14 Years**

(21) Appl. No.: **29/140,848**

(22) Filed: **Apr. 25, 2001**

(51) LOC (7) Cl. **28-02**

(52) U.S. Cl. **D28/8.2**

(58) Field of Search .... D28/8.1, 8.2; D1/100, D1/101, 106, 127; D24/100-102; D11/89, 90; 63/26-28, 29.1, 29.2, 30-32, DIG. 3; 428/15; 510/133, 137-149, 440, 441, 445-449
